(74) Attorney, Agent, or Firm — Alloy Patent Law;
 Walker Griffin Weitzel(57) **CLAIM**

The ornamental design for a self defense phone case frame substantially as shown and described.

DESCRIPTION

FIG. 1 is a bottom-right-front isometric view of a self defense phone case frame showing my new design,
 FIG. 2 is a top-left-back isometric view thereof,
 FIG. 3 is a bottom-left-front isometric view thereof,
 FIG. 4 is a top-right-back isometric view thereof,
 FIG. 5 is a back view thereof,
 FIG. 6 is a front view thereof,
 FIG. 7 is a left view thereof,
 FIG. 8 is a right view thereof,
 FIG. 9 is a top view thereof; and,
 FIG. 10 is a bottom view thereof.
